(57) **CLAIM**

The ornamental design for a section, as shown and described.

DESCRIPTION

FIG. 1 is an end view of a section showing our new design; FIG. 2 is a perspective view of the section shown in FIG. 1 showing the right side view and the top view, the inverted perspective view of the section shown in FIG. 2 being identical thereto; and,

FIG. 3 is a perspective view of the section shown in FIG. 1 rotated through 90 degrees showing the left side view and the top view.

The end view not shown is a mirror image of the end shown in FIG. 1 and the section is of indefinite length.
